UNITED STATES PATENT OFFICE.

FRANCIS GEORGE WILLIAM BRISTOW, OF SYDNEY, NEW SOUTH WALES, AUSTRALIA.

SHEEPSHEARING-MACHINE COMB.

Application filed January 4, 1922. Serial No. 526,978.

To all whom it may concern:

Be it known that I, FRANCIS GEORGE WILLIAM BRISTOW, subject of the King of Great Britain and Ireland, residing at Sydney, 5 New South Wales, Australia, have invented certain new and useful Improvements in Sheepshearing-Machine Combs, of which the following is a specification.

In the machine shearing of sheep, the 10 comb and cutter plates at the forward end of the shearing handpiece are buried under the fleece and cannot be seen by the shearer. The wool is shorn strip after strip, the machine being run at each cut through the marginal portion of the uncut fleece next the shorn area. The traverse of the work is left to right in the case of a "right-hand" shearer and from right to left in the case of a "left-hand" shearer. It is common practice for the shearer to carry the side of the 20 comb exposed overlapping the margin of the last cut so as thereby to take in the fleece at the edge of the new cut and avoid leaving ridges or feathers of uncut wool, the presence of which necessitates double cutting to remove them. The strip of fleece thus removed in each cut is consequently narrower than the comb width, and a proportionately larger number of cuts is therefore required for removal of a given width 30 of fleece. Furthermore, as the shearer cannot observe the comb where it is hidden under the fleece, the skin of the sheep is liable to injury by the digging in of the comb points at wrinkles and folds.

In a known type of comb, provision is made for laterally splaying either or both end teeth of the comb for the double purpose of gathering in the edge portion of 40 the uncut fleece, so that the leaving of uncut ridges will be avoided, and offering the shearer a visible indicator of the comb's position under the fleece so that he will not be required to carry the side of the comb overlapping the already cut area. These features are of great practical utility, but they do not provide against the risk of "digging in" the comb points into the skin of the sheep, for though in some cases the splayed 45 teeth were lengthened slightly the lengthening was incidental to the splaying and was not directed to and was not effective for the purposes of the present invention. The present invention aims at the provision of 50 means whereby the risk of cutting the sheep

is minimized irrespectively of the lateral splaying of the outer teeth of the comb to obtain an indication to the shearer that the comb is gathering in the margin of the fleece and not leaving a feather of uncut wool next 60 the margin of the preceding cut.

In the case of the known feature of the laterally splayed end tooth or teeth, a practical difficulty has been met in that repeated grinding of the comb face ultimately brings 65 the splayed tooth end to a sharp point. This sharp point is apt to enter the skin of the sheep at folds or creases and make cuts or tears therein. The present invention includes means whereby this objectionable condition is obviated.

The present invention therefore consists in forwardly extending the end teeth of the comb substantially beyond the arc formed by the tips of the intermediate teeth, and in downbending such extended portions of the end teeth so that their tips will not be touched in regrinding the comb, and thereby sharpened. The extended tooth ends are preferably formed somewhat heavier in section than the ends of the intermediate teeth and are finished off smoothly to blunt ends, which cannot, by any normal force applied in use, be driven into the sheep's skin. The extended ends may be outbent or splayed to 85 obtain the advantage of the known construction in which the normal end teeth are laterally outbent or splayed as already described. The forward extensions of the end teeth may be integral with the comb structure, but may be procured by fitting adapter extension shoes to standard combs having 90 normal teeth.

In the accompanying explanatory drawings:—

Fig. 1 is a plan view of a comb having the right hand side or "bottom" tooth extended forwardly, downbent, and splayed outwardly;

Fig. 2 is a similar view of a like comb 100 having the invention applied to the left hand side or "top" tooth;

Fig. 3 is a similar view in which the invention is shown applied to the "top" and to the "bottom" teeth of a comb;

Fig. 4 is a fragmentary view similar to Fig. 1;

Fig. 5 is a side elevational view corresponding to Fig. 1 and clearly showing the downbent and blunt top features;

Fig. 6 is a sectional plan view of a "top" teeth extension shoe;

Fig. 7 is a fragmentary plan view showing the fitting of the attachment Fig. 6 to a 5 normal tooth comb; and

Fig. 8 is a broken plan view showing the fitting of a full width extension shoe having a straight extensions for both end teeth of a normal comb.

10 In these drawings, 1 designates a comb having a pair of end teeth 2 and a plurality of intermediate teeth 3. One or both of said end teeth 2 are provided with a forward extension 2^a which measures about a quarter 15 of an inch more or less in advance of the arc formed by the tips of the intermediate teeth 3—that is sufficient to form a riding horn or riding horns 4 to run on the skin of the sheep, and the lateral splay is about 20 sufficient to obtain a "gather" equal to that which would be obtained by making the comb one tooth wider on either side. The downbending (Fig. 5) extends from the tooth face trim line (a) forwardly for two- 25 thirds more or less of the thickness of the comb plate, as it is in new condition before regrinding.

The effect of forwardly extending either 30 or both end teeth 2 of the comb 1 is to facilitate entry of the comb into the fleece, and to stretch the skin of the sheep and hold it clear of the points of the intermediate teeth 3. The smooth blunt extensions or "horns" 4 ride easily over the skin. The 35 intermediate teeth 3 are therefore not blocked in the advance movement by digging into the sheep's skin, and the work of the shearer is lightened and facilitated.

When the extension 2^a is obtained by 40 means of a shoe plate 5, for either end tooth 2 (Figs. 6 and 7) or for both end teeth (Fig. 8) said plate 5 is formed as a stamping in sheet metal to set under the comb, its "horn" or "horns" 4 being, when 45 so desired, splayed outwardly and downbent. The single or full width shoe plate is secured in position by the usual fixing screws by which the comb is held on the lower jaw of the shearing handpiece.

What I claim as my invention and desire to secure by Letters Patent is:—

1. A sheep shearing machine comb comprising a plurality of intermediate teeth, and an end tooth extending beyond the arc formed by the tips of the intermediate teeth, said extended tooth being outwardly splayed, the extended portion of said tooth being downwardly curved and the tip thereof blunted. 55

2. A sheep shearing machine comb comprising a pair of end teeth, and a plurality of intermediate teeth, said end teeth extending beyond the arc formed by the tips of the intermediate teeth, said extended teeth being outwardly splayed and the tips thereof blunted, the extended portion of each of said end teeth being of greater cross section 60 than the intermediate teeth. 65

3. A sheep shearing machine comb comprising a plurality of teeth, one of the end teeth having a downwardly curved and forwardly extended riding horn. 70

4. A sheep shearing machine comb comprising a plurality of teeth, one of the end teeth having an outwardly splayed, downwardly curved and forwardly extended riding horn. 75

5. A sheep shearing machine comb comprising a plurality of teeth, and a shoe disposed on one of the end teeth of said comb, said shoe being outwardly splayed, downwardly curved, and forwardly extended beyond the tips of the intermediate comb teeth. 80

6. A sheep shearing machine comb comprising a plurality of teeth, and a shoe disposed on each of the end teeth of said comb, said shoes being outwardly splayed, downwardly curved, and forwardly extended beyond the tips of the intermediate comb teeth. 85

7. A sheep shearing machine comb comprising a plurality of teeth, and a shoe disposed on one of the end teeth of said comb, said shoe being outwardly splayed, downwardly curved, and forwardly extended beyond the tips of the intermediate comb teeth 90 and having the tip thereof blunted. 95

In testimony whereof I affix my signature.

FRANCIS GEORGE WILLIAM BRISTOW.
